UNITED STATES PATENT OFFICE.

RICHARD W. HUBBARD, OF ASHTABULA, OHIO.

HINGE.

Application filed June 6, 1924. Serial No. 718,400.

To all whom it may concern:

Be it known that I, RICHARD W. HUBBARD, a citizen of the United States, residing at Ashtabula, in the county of Ashtabula and State of Ohio, have invented new and useful Improvements in Hinges, of which the following is a specification.

My present invention pertains to door hinges and it contemplates the provision of 10 a hinge that is adapted for use as lower or tail hinge on a swelled body vehicle such for instance as coupes, sedans, coaches and the like.

The invention further contemplates a 15 hinge for use in connection on the style of vehicle above set forth and is so constructed and arranged that when the door is closed the hinge will be concealed and during the opening of the door the same will be carried 20 away from the body frame portion irrespective of the character of the swell of said body.

The invention further contemplates the provision of a lower or tail hinge that is 25 quickly detachable, due to the fact that the joints swing into the middle of the space between the door and frame when the door is open and at the same time, my novel hinge at all times, finds its own alignment with 30 respect to the upper hinges of the door regardless of their nature.

Other objects of the invention will be 35 fully understood from the following description and claims when the said are read in connection with the drawings accompanying and forming part of this specification, in which

Figure 1 is a view showing a door and 40 door-frame in section and the manner in which the major portion of my novel hinge appears in side elevation when attached to the door and frame.

Figure 2 is a sectional view of the door, 45 frame and hinge in closed position.

Figure 3 is a view similar to Figure 2 and showing the door in open position with respect to the frame.

Fig. 4 is a front elevation of the hinge.

Figure 5 is a view similar to Figure 1 and 50 showing a modified form of hinge.

Figure 6 is a view similar to Figure 2 in which the modified form of hinge is employed.

55 Figure 7 is a view similar to Figure 3 showing the modified construction of hinge.

Similar numerals of reference designate corresponding parts in all the views of the drawings.

The door D and frame F are of the ordinary well known construction and adapted to be interposed between the door and frame is my novel hinge H that comprises the leaf sections 1, 2, 3 and 4 which leaves are secured to each other by means of the pintles 5 and two of the leaves are secured one to the door and the other to the frame by means of the fastenings 6 that enter the openings 7 of the respective leaves.

By reference to the drawings it will be noted that the center pintle receiving portion of the double jointed leaf is provided with a projection 8 whereby limitations of the movement of the otherwise unrestricted leaves is accomplished.

It will be manifest, by reference to the drawings, that the leaves 1 and 4 are countersunk and that the pintle portions toward the outer surface of the door are morticed whereby a slight space of approximately one-eighth of an inch is provided between the door and frame when the door is in its closed position. Because of the construction and joints of my hinge the same is adjustable to any condition that occurs in a vehicle body and may be employed with any kind of upper hinges and solves the necessity of using a protruding hinge on the lower end of the door even when concealed hinges are used on the door above the swell thereof. The hinge is secured onto the door and frame alike with the double joint toward the outside of the door and is morticed into the wood so that their edges are flushed with the surfaces and the positive stop 8 prevents opening of the leaves beyond the center thereby preventing any mishap and locking action of the leaves.

I would distinctly have it understood that the construction herein illustrated and referred to above, is my preferred construction in which four leaves are shown but three more or less leaves may be employed without departing from the scope of my invention.

In order to add greatly to the finished appearance of a vehicle, it is sometimes desirable to construct the leaves of the hinge of round or hexagon stock and therefore I illustrate and now particularly refer to the modified form of construction shown in

Figures 5 to 7 inclusive, in which the door is indicated by D and the frame by F and the hinge as a whole by H and said hinge comprises two leaves 11 and 12 that are joined to each other by means of the connecting plate 10 and the said plate and leaves are detachably arranged by means of the pintles 13. On their ends adjacent the door and frame the leaves 11 and 12 are secured by means of the pintle 13 to fastening screws 14 having the flat head 15.

It will be manifest that this construction of hinge is secured in the door and frame alike with the screws toward the outside 15 of the door which is exactly reversed to the flat form of hinge connection shown in the preferred construction. The round stock as will be noted particularly in Figure 5 at the abutting edges of the leaves is curved and 20 in opening and closing of the door, the abutting edges will ride until they become aligned straight with each other when because of their straight edge surfaces, further movement of the leaves will be prevented.

It will be manifest, that in both the preferred and modified construction, the leaves may be disconnected without removing the hinge from the door or frame and therefore 30 painting of a door and vehicle body may be readily accomplished. The two constructions of hinge are inexpensive to produce and are easily connected and disengaged

when desired and they comprise no delicate elements that are liable to become inoperative after a short period of use.

Having described my invention, what I claim and desire to protect by Letters Patent is:—

1. A hinge having two body portions 40 hingedly connected to each other and having their meeting edges rounded on one surface whereby the body portions may be brought to bear parallel with respect to each other and further adapted to be arranged in alignment with respect to each other, and fastening means secured to the body portions and having a head pivotally secured in the body portions and limited as to movement in one direction.

2. A hinge comprising two body portions having slots in the ends thereof, fastening means pivotally hinged in the slots at one end of the body portions; said fastening means having a head that is provided with a flat straight surface and rounded on the edge thereof whereby the fastening means may be moved in one direction with respect to the body portion, and a link pivotally connected within the slots of the body portions opposite the fastening means and having its ends partially rounded throughout.

In testimony whereof I have hereunto set my hand.

RICHARD W. HUBBARD.
